UNITED STATES PATENT OFFICE.

ABDALOM BEANS, OF ROSCOE TOWNSHIP, DAVIS COUNTY, IOWA.

CAR-COUPING.

SPECIFICATION forming part of Letters Patent No. 269,168, dated December 19, 1882.

Application filed May 9, 1882. (Model.)

To all whom it may concern:

Be it known that I, ABSALOM BEANS, of Roscoe township, in the county of Davis, and in the State of Iowa, have invented certain new and useful Improvements in Car-Couplings; and I do hereby declare that the following is a full, clear, and exact description thereof, reference being had to the accompanying drawing, and to the letters of reference marked thereon, making a part of this specification.

This invention has for its object to provide a car-coupler in which both the links and coupling-pin will be dispensed with, and which will automatically couple when the cars are brought together and can be uncoupled without passing between the cars, as more fully hereinafter specified. These objects I attain by the means illustrated in the accompanying drawing, which represents a view, partly in side elevation and partly in section, of my improved car-coupler.

The letter A indicates one of the draw-heads of a car, which is provided with an extension, B, having a ball, C, at its extremity.

The letter D indicates the draw-head of the opposite car, which is constructed of two parts, hinged together at E, and provided with a recess, F, for the ball of the first-mentioned draw-head. The draw-head D is provided with a flaring mouth, G, and a narrow throat, H, leading to the recess F.

The letter I indicates a flat spring, secured to one portion of the draw-head D, its free end bearing against the other portion in such manner as to hold the two parts together nor-

mally, but permits them to be automatically separated when the ball enters, and when fully entered close upon the ball and couple the cars.

The letter M indicates a lever, which may be fulcrumed to the cross-timbers of the car or to the draw-head, as represented in the drawing. The said lever is connected to the spring by means of a rod, N, secured to an eye, P, at the forward end of said spring.

The operation of my invention will be readily understood in connection with the above description, and is as follows: When the cars come together the ball on one draw-head enters the flaring mouth of the other, forcing the parts asunder until the ball enters the recess therein, when the parts close. To uncouple the cars the lever is operated to elevate the spring, releasing its pressure upon the draw-head and permitting the ball to pull out.

Having thus described my invention, what I claim, and desire to secure by Letters Patent, is—

In combination with the draw-head D, constructed in two parts, and the spring I for holding the upper part in normal position, the lever M, pivoted to the upper side of the draw-head, and the link N, connecting the said lever to the spring, substantially as and for the purposes specified.

In testimony whereof I affix my signature, in presence of two witnesses, this 17th day of April, 1882.

ABDALOM BEANS.
